UNITED STATES PATENT OFFICE.

CHARLES A. WULF, OF INDIANAPOLIS, INDIANA.

FLUSHING-VALVE.

966,509.

Specification of Letters Patent. Patented Aug. 9, 1910.

Application filed June 25, 1909. Serial No. 504,259.

To all whom it may concern:

Be it known that I, CHARLES A. WULF, a citizen of the United States, residing at Indianapolis, in the county of Marion and State of Indiana, have invented certain new and useful Improvements in Flushing-Valves, of which the following is a specification.

The object of my invention is to produce a flushing valve, especially adapted for use in connection with waterclosets, in which there is a total absence of the ordinary controlling floats and in which the closing of the valve will be controlled by the pressure 15 of outflowing water from the flushing supply.

The accompanying drawings illustrate my invention.

Figure 1 is a central vertical section; Fig. 2 a fragmentary similar section of a modified form; Fig. 3 a detail of the structure shown in Fig. 1, showing the position of the parts when the initial valve is first opened and Fig. 4 a similar detail showing 25 the positions of the parts during free outflow from the flushing supply.

In the drawings 10, indicates a tight closed tank of suitable capacity (for an ordinary watercloset of about four or five 30 gallons) having an inlet and outlet opening 11 in its bottom. Connected with opening 11 is a tube 12 into which leads a supply pipe 13. In order to prevent a noisy flow of water from pipe 13 into tube 12 I find 35 it advisable to mount, within tube 12, a guard ring 14 which thus forms an annular space 15 into which the water from pipe 13 first passes, passing from thence downward beyond the outwardly flared depending 40 flange 16 of guard 14, and thence into guard 14 and up through tube 12 into tank 10. Secured to the lower end of tube 12 by a suitable coupling 17 is the main body 18 of the valve proper. Formed within body 18, 45 some distance below the lower end of guard 14, is an annular valve seat 19 which surrounds the upper end of the outflow passage 21. Mounted within the outflow passage 21 and guided therein by a suitable and usual 50 spider is a valve member 22 carrying a packing ring 23 adapted to seat upon the face of the valve seat 19, said packing ring being held in place by means of a suitable retaining cup 24 threaded upon the upper end of 55 valve 22. Valve 22 is tubular and mounted

in the fore thereof is a spider 25 upon the upper end of which is threaded a cup 26 which serves to hold in place a packing ring or valve 27 which seats upon an annular valve seat 28 formed at the upper end 60 of valve 22 around the bore thereof. Spider 25, near its lower end, is provided with shoulders 29 adapted to engage shoulders 31 formed on the valve 22 and thus limit the movement of the valve relative to seat 65 28. In order to move the two valve members upwardly away from their seats against the pressure of water within tank 10, I journal, in casing 18, a shaft 33, the inner end of which projects into the casing and is provided with a crank arm 34 carrying a wrist pin 35 which projects into a slot 36 formed in the lower end of a link 37, the upper end of which is connected to spider 25. Secured to the outer end of shaft 33 is an operating 70 handle or lever 38 which has sufficient weight to pull the valves down upon their seats. Shaft 33 has its axis arranged to one side of the axis of the valves for a purpose which will appear. 80

The operation is as follows:—With the parts in the position shown in Fig. 1, water introduced into tank 10 through pipe 13, will act upon the upper faces of the two valve members to hold them to their seats 85 19 and 28, forming an air cushion in the upper end of the tank. When lever 38 is raised the valve 26—27 will first be withdrawn from its seat 28 and this may be done 90 with comparative ease because the valve is comparatively small, the parts coming into the position shown in Fig. 3. The water will begin to flow through the bore of the valve member 22 whereupon further upward movement of the lever 38 will serve to 95 drive the valve member 22 away from its seat 19 thus permitting a free flow of water from the tank 10 out through the outflow passage 21. Lever 38 is moved upwardly until arm 34 is brought into engagement 100 with the side wall of casing 18, as shown in Figs. 2 and 4, at which time the center of crank pin 35 has been carried beyond the axis of the valve so that the pressure of the flowing water upon the upper faces of the two valves will serve to hold lever 38 from 105 downward movement and thus the valves will be held open. The weight of lever 38 is just enough to bring the valves to closed position when there is about eight ounces 110

of pressure upon the upper faces of the valves and consequently, as soon as the outflow from tank 10 has been sufficient to reduce the pressure therein to approximately a half pound, (more or less depending upon the weight of lever 38 tending to produce return movement of shaft 33) the said lever will serve to automatically return the valves to closed position and thus cut off the flushing flow.

Actual practice has demonstrated that the valve mechanism operates with certainty and uniformity. It will be seen that, by closing the supply valve 51, which is in the feed line leading to pipe 13, and disconnecting coupling 17, the entire valve mechanism may be readily withdrawn for the removal of sediment and for the replacement of the packing rings 23 and 27.

In the form shown in Figs. 1, 3 and 4, there is a continuous inflow of water from the supply pipe 13 during the flushing action. In the modification shown in Fig. 2 this inflow is prevented during the major portion of the flushing flow. In the structure shown in Fig. 2 all of the parts are identical with the parts similarly designated in Fig. 1, but guard 14 is omitted. In this form the supply pipe 13' is closed at its inner end and communicates with the interior of the tube 12 by means of two axially aligned openings 52 and 53 into which a pin 54 carried by cap 26, is projected during the time the valves are in open position, as clearly shown in Fig. 2. The pin 54 does not need to fit openings 52 and 53 very tightly but, by entering said openings, the inflow of water from pipe 13' during the time the valves are in open position, is practically stopped.

It is to be understood that, while I have shown the valve members as being composite in order to facilitate the opening thereof against accumulated pressure, yet my invention is by no means limited to such a construction, for it is readily apparent that the two nested valve members might be readily unified without in any manner changing the operation of the device other than increasing the amount of force necessary to get an initial opening thereof.

In the normal operation of my device it is entirely probable that the velocity of outflow from the apparatus to the bowl will decrease, as the amount of water and pressure in the tank decreases, to a sufficient extent to gradually diminish the flow from the bowl and thus provide a filling flow before the pressure upon the upper faces of the valves is decreased to a point where the operating lever 38 will serve to close the valves, but, in order to insure a filling flow subsequent to the flushing flow, it is entirely feasible to provide, around the valve seat 19, an annular recess 41 in which I mount a spring 52

adapted to engage the valve 22 and serve to hold the same open until a sufficient pressure has accumulated above the valve. The spring 42 will serve to hold the packing ring 23 when a short distance above the valve seat 19, this distance being less than enough to accommodate the full flow entering tube 12 from pipe 13, so that whenever the valve is brought down upon the spring, there will inevitably be a gradual accumulation of pressure on top of the valve so as to insure its ultimate closing, although there will be for a short time a flow of sufficient amount to insure the refilling of the bowl after it has been flushed.

I claim as my invention:

1. In a valve structure having a valve seat, a valve movable toward and from said seat, an operating member, and intermediate connections between said operating member and the valve arranged in such manner that pressure upon the valve toward its seat will normally tend to drive the operating member in closing direction but, when the valve is in open position will tend to drive the operating member in opening direction, whereby pressure upon the open valve in excess of the normal closing force of the operating member will serve to hold the valve open.

2. In a flushing valve, the combination with a closed flushing tank, having a supply pipe leading thereto and an outflow passage leading therefrom, of a valve arranged between the tank and outflow passage, an operating member, and a crank connection between said operating member and the valve, whereby pressure upon the valve tending to close the same will act upon the operating member to move it in either direction depending upon the position of the valve, for the purpose set forth.

3. A valve structure comprising a main body having a valve seat, a valve arranged to cooperate with said seat, an inlet structure arranged within the main body and having openings communicating therewith, and a filling member carried by the valve and cooperating with the openings in the inlet structure when the valve is opened to reduce inflow, for the purposes set forth.

4. In a valve structure having a valve seat, a valve movable toward and from said seat, an operating member, and intermediate connections between said operating member and the valve arranged in such manner that pressure upon the valve toward its seat will normally tend to drive the operating member in closing direction but, when the valve is in open position will tend to drive the operating member in opening direction, whereby pressure upon the open valve in excess of the normal closing force of the operating member will serve to hold the valve open, an inlet structure arranged within the main body and having an opening communicating there-

with, and a member carried by the valve for coöperating with said opening to decrease inflow while the valve is open.

5. A valve structure comprising a main body having a valve seat, a valve adapted to be seated upon said seat, an operating shaft, a weighted operating lever carried by said shaft, and a crank connection between the operating shaft and valve, for the purpose set forth, an inlet structure arranged within the main body and having an opening communicating therewith, and a member carried by the valve for coöperating with said opening to decrease inflow while the valve is open.
6. A valve structure comprising a main body having a valve seat, a valve adapted to be seated upon said seat, an operating shaft arranged to one side of the axis of the valve, a weighted operating lever carried by said shaft, and a crank connection between the operating shaft and valve, for the purpose set forth, an inlet structure arranged within the main body and having an opening communicating therewith, and a member carried by the valve for coöperating with said opening to decrease inflow while the valve is open.

7. In a flushing valve, the combination with a closed flushing tank, having a supply pipe leading thereto and an outflow passage leading therefrom, of a valve arranged between the tank and outflow passage, an operating member and a crank connection between said operating member and the valve, whereby pressure upon the valve tending to close the same will act upon the operating member to move it in either direction depending upon the position of the valve, for the purpose set forth, an inlet structure arranged within the main body and having an opening communicating therewith, and a member carried by the valve for coöperating with said opening to decrease inflow while the valve is open.

In witness whereof, I, have hereunto set my hand and seal at Indianapolis, Indiana, this sixteenth day of June, A. D. one thousand nine hundred and nine.

CHARLES A. WULF. [L.S.]
